UNITED STATES PATENT OFFICE

169,905

CIGARETTE PACKAGE DISPENSER

Clayton A. Laughlin, Minneapolis, Minn., assignor to Northwest Plastics, Inc., St. Paul, Minn., a corporation of Minnesota

Application March 18, 1952, Serial No. 18,947

Term of patent 14 years

(Cl. D52—2)

To all whom it may concern:

Be it known that I, Clayton A. Laughlin, a citizen of the United States, residing at Minneapolis, in the county of Hennepin and State of Minnesota, have invented a new, original, and ornamental Design for a Cigarette Package Dispenser, of which the following is a specification, reference being had to the accompanying drawing forming a part hereof.

I claim:

The ornamental design for a cigarette package dispenser, as shown.

CLAYTON A. LAUGHLIN.
